MENU HOLDER GUIDE

Raymond O. Fariss, Santa Monica, Calif.

Filed Jan. 28, 1964, Ser. No. 78,391

Term of patent 7 years

(Cl. D44—29)

FIG.1.

FIG.2.

FIG.3.

FIG.4.

FIGURE 1 is a rear elevational view of a menu holder guide showing my new design;

FIGURE 2 is a right side elevational view thereof;

FIGURE 3 is a top plan view thereof; and,

FIGURE 4 is a front elevational view thereof.

The broken line showing of a condiment dispenser fence is for illustrative purposes only.

I claim:

The ornamental design for a menu holder guide, substantially as shown and described.
